UNITED STATES PATENT OFFICE

168,721

LAMP

Rosalie A. Woodin, Wilmington, Calif.

Application May 10, 1952, Serial No. 19,655

Term of patent 7 years

(Cl. D48—20)

To all whom it may concern:

Be it known that I, Rosalie A. Woodin, a citizen of the United States, residing at Wilmington, State of California, have invented a new, original, and ornamental Design for a Lamp, of which the following is a specification, reference being had to the accompanying drawing, forming a part hereof.

Figure 1 is a front elevational view of a lamp showing my new design;

Figure 2 is a side elevational view thereof; and Figure 3 is a top plan view.

I claim:

The ornamental design for a lamp, as shown.

ROSLIE A. WOODIN.
